UNITED STATES PATENT OFFICE

WILLIAM H. HARRIS, OF BROOKLYN, AND GEORGE FARR, OF NEW YORK, N. Y.

STEAM-BOILER FOR LOCOMOTIVES.

SPECIFICATION forming part of Letters Patent No. 252,213, dated January 10, 1882.

Application filed December 7, 1881. (No model.)

To all whom it may concern:

Be it known that we, WM. H. HARRIS, of Brooklyn, Kings county, and GEORGE FARR, of New York, in the county of New York and State of New York, have invented certain new and useful Improvements in Steam-Boilers for Locomotive and other Engines; and we do hereby declare that the following is a full, clear, and exact description of the invention, which will enable others skilled in the art to which it appertains to make and use the same, reference being had to the accompanying drawings, and to the letters of reference marked thereon, which form a part of this specification.

15 This invention relates to improvements in boilers for locomotive and other engines.

The object of the invention is a more economic consumption of fuel, the avoidance of smoke, a more rapid generation of steam, and 20 the absence of sediment and scale in the boiler and on the boiler-plates, the prevention of foaming or priming, the heating of the feed-water preparatory to its introduction into the boiler, and the rapid and constant circulation thereof.

25 Before proceeding further to describe our invention we may state that heretofore many attempts have been made to produce these results by various means, such as feeding heated water, coking of fuel, separating devices for 30 steam and water, and circulating-plates with blow-off and other contrivances, all of which have been more or less successful. We are not, however, aware that the means we employ have ever before been combined and arranged 35 in such manner to produce such beneficial results as will hereinafter be described by such a simple and inexpensive manner. We therefore lay no claim to any of those referred to, as they do not answer our purpose.

40 Referring more particularly to the accompanying drawings, Figure 1 illustrates a vertical longitudinal section of our boiler with a portion of the steam-dome broken away; Fig. 2, a vertical transverse section on the line $\alpha\alpha$ of Fig. 1. Fig. 3 is a detached view of our improved steam-dome with its steam-separators.

45 It is obvious that our invention is applicable to a variety of boilers; but in this case we have shown it as applied to a locomotive-boiler 50 of the ordinary construction; and it consists, first, in the means by which blistering or burning of the boiler is avoided by preventing the

lodgment of sediment where it usually accumulates, and thus the formation of scale is prevented. We may here remark that the effect of this deposit or incrustation on the heating-surfaces is that in proportion to the amount of solid matter accumulated, combined with its non-conducting property, so will the evaporation of water be retarded and the relative 55 plates exposed to the action of the flame be burned, so that two evils come from the same cause—viz., the burning of the boiler-plate and the poor evaporation of steam. Therefore, to remedy this defect is the object of the first feature of our invention.

60 It further consists in the combination and arrangement of means for introducing the proper supply of heated air in such points as will cause complete commingling and admixture of the gases evolved from the fuel in the combustion-chamber, by which means the heat and flame are retarded in their passages, and by such mingling and retardation the said gases are entirely consumed, forming a clear, pure, 65 and fierce heat, thereby avoiding smoke, and producing an economy in fuel. The heat thus produced is made to impinge on the generating-surface of the boiler, which surface, being 70 freed from soot and oxidation, takes up the 75 heat and rapidly transmits it to the water.

The invention further consists in means for producing a rapid circulation of water and heating it before its introduction into the boiler, and also in means for precipitating the sediment and other foreign matter usually carried along with the feed-water into the boiler, and also in means for blowing off said sedimentary 80 deposits before they have time to fasten in the 85 form of incrustation on the sides of the heating-surface.

90 It further consists in separating devices located within the boiler and the steam-dome, whereby the water, when foaming, is prevented from entering the steam-supply pipe, and thus 95 dry clean steam is furnished to the engine, all of which will be further hereinafter described.

A is the boiler, and B the fire-box thereof. C is a pendent partition, straight on top and slightly arched at the bottom. As is not usual, 100 this partition is entirely independent of the boiler crown-sheet and may be made to be adapted to any form of boiler. We prefer to make it independent of the boiler-plates, for the

reason it can adjust itself to any irregularity of the expansion or contraction of the boiler and the boiler from it. It will be observed that a portion of the partition is fire-brick or some such substance, as seen at *a*; but it may be made to conform to the shape of the crown-sheet. Should a small quantity of gases pass between the crown-sheet and the top of the partition when so constructed as last mentioned, it will 5 do no harm. The bottom of the water-partition *C*, as shown, is slightly arching from side to side, the purpose being that any sediment or deposit which takes place will naturally find its way to the lowest corners, which are the 10 coolest in the furnace, and by this means where the fire is the hottest the bottom of the partition is the cleanest, and thus less liable to burn. 15

On the bottom of the water-partition, as described, will be seen a perforated pipe, *G*, (see 20 Fig. 2,) with the perforations facing downward and curved in conformity with the curve of the partition, so that when it is required any sediment or mud which may have accumulated can be efficiently and readily blown off through the 25 mud-pipe *K*.

On one side of the boiler, and through the water-leg in this instance, is shown a feed-water pipe, *J*, which may be attached to an injector or pump in the usual way. This pipe 30 *J* is passed through a thimble and communicates with and feeds the water to the partition, and on the other side of the boiler is shown another pipe, *F*, also connected to the partition near the bottom, and extending up outside, entering the water-leg above the line of the furnace-door, so that it will be seen that the water 35 is fed to the partition, heated in it, and then conducted to the boiler in a pure hot state, parting with all its impurities and leaving them 40 on the bottom of the partition, from whence they are readily blown off.

Should it happen that the outside pipe, *F*, should be in the way, a pipe, as shown in dotted lines on the inside of the partition, may be provided with good results. This pipe *F* can be 45 readily inserted through a hand-hole, which could be made opposite to where the pipe would enter, and in this way we incur only one boring in the side of the water-leg.

50 The perforated blow-off pipe is passed through the feed-water pipe, as shown, and in this way only one hole will have to be made through the water-leg of the boiler.

Centrally is seen through the water-partition 55 a pipe, *c*, through which, in addition to pipe *F*, any steam generated in said partition is conveyed to the boiler-space proper. Thus it will be observed that in addition to heating and purifying the feed-water we produce a large 60 and rapid steam-generating surface and a thorough circulation of the water. The boiler will last much longer on account of its being free from sediment, and foaming will be partially stopped by the purity of the water in the 65 boiler. The bearing-surface of the engine will also last much longer, as no sand or grinding-surface is carried over with the steam.

Just over the partition and pipe *c* we locate an inverted dish or vessel dish-shaped (marked *L*,) the object being to prevent the shooting up 70 into the steam-dome of any water that might, by agitation or otherwise, arise from the water-partition; and above this dish-plate we locate a series of steam-separators or baffle plates for the still further prevention of water getting 75 into the steam-supply pipe.

The arrows made in dotted lines denote dry steam, and the arrows in full lines show the particles of water dropping off the surface of the separating-plates. 80

On the tube-sheet ends of the grates we locate our air-supply apparatus *E*, and we arrange it at this point for two reasons, first, for the protection of the tube-sheets, for it is well known that the wear and tear at this point is greater 85 than at any other; and, second, because it forms a throat, *N*, between it and the lower or bottom end of the partition, through which the gas must pass. The heat at this point is very intense and fully charged with combustible 90 gases, which in the ordinary way could not be supplied with the proper supply of atmospheric air; but with our device we produce a sufficient and constant supply at the very place where it is most needed, and the air, being 95 heated, readily unites with the said gases, when the whole is ignited and burns fiercely, producing an intense heat, entirely consuming the smoke. 100

It will be observed that the air is broken up 100 into fine streams or jets, causing it to take up and unite more freely with the gaseous products of combustion coming in contact with it. Therefore it must be obvious that we produce 105 perfect combustion.

The dotted lines showing a grate-bar indicate that the grate can be raised or lowered as may be required, according to the kind of fuel used.

It is evident the air apparatus can be adjusted 110 with the grate.

Plugs or thimbles may be inserted in the ends of the tubes to protect them, and to also control the flow of heat through the tubes as occasion may require. 115

The dish-shaped vessel may be suspended by any well-known means, one of which is shown by the angle-irons *d*. Safety-valves and other well-known contrivances of steam-boilers are not shown. 120

Having described our invention, what we claim as new, and desire to secure by Letters Patent, is—

1. The combination, in a steam-boiler furnace, of a hollow independent water-partition, arched at its bottom, as described, and perforated air heating and supply apparatus located at and against the rear water-leg, by means of which a narrow throat is formed, whereby the combustible gases and air are forced to mingle 125 and unite for their more complete combustion, as described. 130

2. In a steam-boiler furnace, the independent hollow water-partition, arched at its bottom, as

described, the feed-pipes, the circulating-pipe which connects the partition with the water-leg of the boiler, and the sediment blow-off pipe, the whole combined and arranged to feed, 5 heat, circulate, and purify the water before its introduction into the boiler, in the manner shown and set forth.

3. The combination, in a steam-boiler consisting of the pendent independent partition 10 having an arched bottom, as described, the feed-water and circulating pipes, the blow-off pipe, and the central communicating-pipe, with the steam and water separating devices, all arranged to operate in the manner shown.

15 4. The combination, in a steam-boiler furnace, of the pendent partition, having a flat top for the reception of brick lining and arched bottom for the collection of sediment, and its blow-

off, with an air heating and supplying device, the said partition dividing the furnace-chamber 20 into a front and rear combustion-chamber, whereby smoke and gases are consumed in the manner set forth.

5. The combination, in a boiler, of the hollow pendent partition, connecting-pipe *c*, inverted-dish-shaped vessel *L*, separating-plates 25 in steam-dome *M*, and dry-steam pipe *O*, all arranged as set forth.

In testimony that we claim the foregoing as our own we affix our signatures in presence of 30 two witnesses.

WILLIAM HENRY HARRIS.
GEORGE FARR.
